Specification for Design.

Patented July 24, 1917.

Application filed June 7, 1917. Serial No. 173,394. Term of patent 7 years.

To all whom it may concern:

Be it known that I, RAYMOND V. OWEN, a citizen of the United States, and a resident of St. Louis, county of St. Louis, State of Missouri, have invented a certain new, original, and ornamental Design for an Ornamental Lighting-Fixture, whereof the following is a specification, reference being had to the accompanying drawings, forming part thereof.

In the accompanying drawings, Figure 1 is a plan view of the ornamental lighting fixture embodying my new design and Fig. 2 is a side elevational view of said fixture.

I claim:

The ornamental design for an ornamental lighting fixture substantially as shown.

In witness whereof, I have hereunto set my hand this 5th day of May, A. D. 1917.

RAYMOND V. OWEN.
